EXCAVATING SYSTEM

Application filed October 11, 1929. Serial No. 398,837.

This invention relates to an excavating system or apparatus especially designed and adapted for use in constructing levees although also capable of advantageous use in connection with other excavating or earth handling projects.

The necessity of constructing appropriate levees to protect the flood areas of certain rivers has raised a very serious problem, especially in view of the vast quantities of earth that must be excavated and handled to build levees of appropriate size throughout the extensive flood areas of certain rivers. Various expedients have been suggested but prior to the present invention none have been found adequate to cope with the problem.

One of the principal objects of the present invention is to provide a system or apparatus of the character mentioned which combines continuous and speedy excavating or digging on a large scale at the borrow pit (from which the earth is taken) with efficient and expeditious handling or transferring of the earth so excavated whereby the dirt or earth taken from the borrow pit is built up into a levee at a minimum cost.

Another important object of the invention is to provide an apparatus or system of this character and having these advantages and which avoids the use of highly expensive and special equipment by combining and organizing slightly modified standard instrumentalities for digging and hauling in a novel and practical manner.

A further object is to provide an excavating apparatus or system adapted for this purpose and yet readily mobile so that it can progress along the river as the levee is built.

In carrying out the present invention any ordinary excavating means may be used for digging. Thus, a clam shell, drag line, power shovel, or the like, may be employed but usually a drag line is utilized. The drag line stands on the unexcavated area although its drag line bucket operates in the borrow pit or area to be excavated. The levee to be constructed is spaced backwardly from the river edge of the borrow pit a substantial distance and for transferring the earth exca-

vated from the borrow pit to the location on which the levee is to be formed, wheeled carriers, such as crawler wagons, are provided. One end of each crawler wagon is connected to a haul-back cable which extends to the drum of a haul-back hoist mounted on skids on the river side of the borrow pit and suitably anchored in place when excavating any particular area. The other end of each crawler wagon is connected to one end of a haul-in cable extending up over pulleys on the upper and outer end of the boom of a power crane and then down to and around a high speed drum driven by the power plant of the crane. The outer end of the boom of the crane is maintained at an appropriate elevation and the boom and crane have the desired stability imparted thereto by means of an adjustable strut or stiff leg, the upper end of which is connected to the outer end of the boom in supporting relation thereto and the lower end of which rests on a suitable mat or base. On the outer and upper end of the boom an operator's cab is provided and contains the controlling levers for the instrumentalities of the crane, these controlling levers being connected by suitable motion transmission means to control devices ordinarily provided on the crane. With this organization the digging is not dependent in any way and is not slowed up by the hauling of the earth from the borrow pit to the levee site. Continuous digging may be carried on especially as a plurality of crawler wagons are provided so that as one crawler wagon is being hauled in to the levee site the other is being loaded by the excavator.

While various types of movable carriers may be provided for transferring the earth from the borrow pit to the levee site, preferably the movable carrier has its body mounted on a frame carried by free running endless treads or self laying tracks. The body of the wagon has the usual sides but one end thereof is open. A sliding gate normally closes the other end thereof and is so connected to the haul-back cable and haul-in cables and otherwise so controlled that when the crawler wagon reaches the location on the levee site at which the dirt

55

60

65

70

75

80

85

90

95

100

is to be discharged the haul-back and haul-in cables may be utilized to move the sliding gate toward the open end of the wagon to discharge the earth from the wagon and there-
5 after to return the gate to its normal position.

Each flexible tread has an independent
10 brake, so that by applying the brake on one
side or to one tread and thereby holding
such flexible tread stationary or retarding
15 the movement thereof while the other tread
is left free running, the crawler wagons may
be individually steered.

Other objects and advantages reside in
15 certain novel features of the construction, ar-
rangement and combination of parts which
will be hereinafter more fully described and
particularly pointed out in the appended
20 claims, reference being had to the accompany-
ing drawings, forming a part of this speci-
fication, and in which:

Figure 1 is a plan view illustrating dia-
grammatically an excavating system em-
bodying the present invention;

Figure 2 is a view similar to Figure 1 but
25 showing the system in side elevation;

Figure 3 is a view in side elevation show-
ing the crane and its adjustable stiff leg
employed for hauling wheel carriers to the
levee site;

30 Figure 4 is a view in front elevation illus-
trating the adjustable stiff leg and the oper-
ator's cab.

Figure 5 is a view in top plan illustrating
35 one of the wheeled carriers or crawler wagons
employed for transferring the earth from the
borrow pit to the levee site;

Figure 6 is a view of the crawler wagon
in side elevation;

Figure 7 is a diagrammatic view illustrat-
40 ing the reeving of the haul-back and haul-in
cables on the crawler wagons;

Figure 8 is a fragmentary view in rear
elevation showing the foot pedals and asso-
45 ciated mechanism employed for independ-
ently operating the brakes;

Figure 9 is a view in longitudinal vertical
section and partly in side elevation showing
50 how each foot pedal is connected to its brake;
and

55 Figure 10 is a detail view in section taken
on line 10—10 of Figure 9.

Referring to the drawings and more par-
ticularly to Figures 1 and 2, it will be seen
55 that the excavating system embodying the
present invention proposes generally a suit-
able excavator 1 which may be of any suit-
able type although illustrated as a conven-
tional drag line excavator. The truck of the
excavator stands on unexcavated ground but
by virtue of its boom, the drag line bucket
thereof takes the earth from the excavated
area or what is known as the borrow pit.
After any particular area has been excavated
65 to the desired extent, the excavator 1 is moved

away from the excavated area so that the
excavation may progress as desired.

The earth taken from the borrow pit is
utilized to build up a levee at a substantial
70 distance from the land side of the borrow
pit and for the purpose of transferring the
excavated earth from the borrow pit to the
levee site wheeled carriers such as crawler
75 wagons designated generally at 2 are pro-
vided. Preferably, a plurality of crawler
wagons 2 are utilized, two being shown. The
crawler wagons 2 are of identical construc-
80 tion and will be described more in detail here-
inafter. At one end each crawler wagon is
connected to one end of a haul-in cable 3 and
at its other end each crawler wagon is con-
nected to one end of a haul-back cable 4. The
haul-in cables 3 extend over suitable
85 guide pulleys 5 provided at the upper and
outer end of the boom 6 of a crane designated
generally at 7. After passing over the pul-
leys 5, the cables 3 extend down to and
around high speed drums 8 mounted on the
revolving platform of the crane and driven
90 from the power plant thereof in a conven-
tional manner, as will be hereinafter more
fully described. In order to impart stability
to the crane and also to reinforce the boom,
the outer end of the boom is supported by
95 an adjustable spud or stiff leg designated
generally at 10.

The end of each haul-back line 4 opposite
to that connected to its crawler wagon is
wound around a drum 11 provided therefor
on a conventional drag line hoist 12. There
100 are two drums 11 on the hoist 12, one for
each line 4. The hoist 12 is supported on
suitable skids 13 so that it may be moved
along as the excavating progresses. How-
ever, in excavating any particular area, the
105 hoist 12 is anchored in position as indicated
at 14. As will be apparent from Figures 1
and 2, the hoist 12 is located adjacent the
river edge of the borrow pit and the crane 7
is located adjacent the land side of the levee
110 site.

Referring now particularly to Figures 5
and 6, it will be seen that each crawler wagon
2 has a body including a bottom 15 and sides
15, the body being supported on a truck 17
equipped with endless flexible treads or self
laying treads 18. One end of the body of the
wagon is open but the other end thereof is
normally closed by a sliding gate designated
generally at 20. The gate 20 is suitably braced
and reinforced as shown in the drawings
and it has an enlarged base provided with
rollers 21 which ride on the bottom 15 of the
wagon body. If desired, cooperating guides
120 may be provided between the sides of the
wagon body and the sliding gates 20.

Beyond the sliding gate, the framing of
the bottom of the wagon body is extended to
provide a platform on which an operator's
125 seat 22 is mounted.

The present invention proposes to utilize the cables 3 and 4 to haul the wagons back and forth and also to move the sliding gate 20 relative to the wagon body to discharge the dirt or earth out of the open end of the wagon body at the levee site. In order that the wagon may be held stationary during this discharging movement of the gate 20 conventional brakes 25 are provided for the flexible treads or belts 18. Normally, the belts or flexible treads 18 are free running but when both brakes 25 have braking engagement with the drums 25', then the treads 18 are held against movement and consequently the wagon is held stationary. It is to be understood that the brake drums 25' are fixed to shafts 18' which in turn are keyed or otherwise fixed to sprocket wheels 19 intermeshed with the links of the flexible treads so that when the drums 25' are held against movement the flexible treads are likewise held.

When the brakes 25 are operated simultaneously they serve to hold the crawler wagon against movement to permit the cables 3 and 4 to move the sliding gate. In order that the brakes may also be utilized to steer the crawler wagons, individual or independent operating means is provided for each brake. Thus, as shown in Figure 9, each brake 25 has one end anchored or dead-ended as at 26' on a bracket 26 and the opposite end of each brake has an attaching lug 27 pivoted as at 27' to spaced arms 28' of a sleeve 29, the sleeve being rotatably fitted on a pin 29' carried by the bracket 26. Each sleeve 29 has a brake operating lever 30 integral therewith or otherwise suitably secured thereto. The outer end of each brake operating lever is pivotally connected to one end of a rod 31 and the opposite end of each rod is pivotally connected to the outer end of a crank arm 32 fixed to one end of a shaft 33. The shafts 33 are journaled in bearings 33' provided therefor at the rear of the crawler wagon and these shafts, although independently rotatable, are alined. Each shaft 33 has an operating arm 34 fixed thereto and carrying a foot pedal 34'. The foot pedals 34' have ratchet bars 35 fixed thereto and cooperable in the usual way with keeper plates 35' fixed to the structure at the rear of the crawler wagon. As shown in Figure 6, the foot pedals 34' are located within convenient reach of the operator and provide means whereby the brakes may be individually or simultaneously engaged.

The haul-in lines 3 and haul-back lines 4 after being reeved in a novel manner on drums or pulleys provided on the wagon body are connected to the sliding gate 20. The reeving of these lines 3 and 4 will be best understood by comparing Figure 7 with Figures 5 and 6. As shown in Figure 7, the haul-in line 3 is connected to an equalizer bar

36 and to the ends of bar 36, cables 37, 38, 39 and 40 are secured. The cables 38 and 40 are extended back and around vertical pulleys 41 and 42, thence around lower horizontal pulleys 43 and 44 and from the pulleys 43 and 44 back to the gate 20 to which they are secured as indicated at 45. The cables 37 and 39 are extended from the bar 36 back to lower vertical pulleys 46 and 47, thence upwardly from these pulleys 46 and 47 to upper vertical pulleys 48 and 49, then around upper horizontal pulleys 50 and 51 and back along the wagon body to the gate to which they are connected as indicated at 52.

Each haul-back cable 4 is wound around a drum 55 fixed to a shaft 56 journaled in suitable bearings provided on the frame of its wagon below the operator's platform. On this same shaft 56 other drums designated at 57, 58, 59 and 60 are also fixed and have cables 61, 62, 63 and 64 secured thereto, wound thereabout and connected to the sliding gate. The cables 61 and 63 extend directly from their drums to the sliding gate but the cables 62 and 64 extend up over pulleys 65 and thence to the point of their connection with the gate.

For the purpose of normally holding the shaft 56 against rotation, and thereby maintaining the gate 20 against movement, the drum 55 has a flange with which brake band 66 coacts, this brake band being applied or released by means of a hand lever 67 which may be latched in a conventional manner to a quadrant 68 and which is connected by means of a crank arm 69, connecting rod 70 to the brake operating lever 71. If desired, the shaft 56 may also have a ratchet wheel 72 fixed thereto. Where the ratchet wheel is employed, a pawl 73 is mounted on the frame and may be engaged with or disengaged from the ratchet wheel by means of a suitable control rod 74 (see Figure 5). When the pawl 73 engages the ratchet wheel 72 the shaft 56 is positively locked against rotation.

As previously described, the haul-in lines 3 extend up over guide pulleys on the outer end of the boom 6 of the crane 7. This crane has the usual revolving platform 75 supported in a conventional manner on a truck 76 equipped with self laying tracks or endless flexible treads 77. The boom 6 has its lower end pivoted to the platform 75 and is vertically adjustable under the control of conventional hoisting tackle 78 actuated from one of the drums 79 on the revolving platform. While building up any particular section of the levee the boom 6 is vertically adjusted from time to time as may be necessary or appropriate to the particular phase of the operation. As shown in Figure 3 an operator's cab 80 is supported on the upper and outer end of the boom 6 and in this cab control levers 81 are provided and are connected by rods 82, bell crank levers 83 and rods 123

84 or other suitable motion transmission mechanism to the usual controls on the revolving platform. The rods 82 may consist of interfitted or telescoped sections freely adjustable as to length but constrained to rotate together in all adjustment whereby the boom 6 may be raised and lowered without impairing the connection of levers 81 with the controls on the revolving platform 75. In this way the operator in the cab 80 may control the action of the crane. In other words, he may cause the platform to revolve, the boom to be raised and lowered, or the drums to be driven and all this from the cab 80. 15 As the cab 80 is supported at the outer and upper end of the boom the operator in the cab has full view of the entire system and may conveniently signal or receive signals from the operators on the crawler wagons, and on the hoist 12. 20

The adjustable stiff leg or spud 10 is made up of a plurality of sections, such as sections 85, 86 and 87 telescoping one within the other, the lower section being pivoted to a suitable mat or base 88 and the upper section being pivotally connected to the upper and outer end of the boom. While the sections 85, 86 and 87 are of progressively increasing size in order to permit of the telescoping of one into the other, they are otherwise of identical construction and each includes a pair of channel side members 90 rigidly connected together and maintained in spaced relation by cross braces 91. The channel side members slide one into the other. 35

The sections 86 and 87 are releasably locked in any particular adjustment relative to each other by suitable means, such as spring projected bolts 92 coacting with registering openings 93 of the sections. Similar bolts designated at 92' coact with openings 93' provided in the section 85 and adapted to register with openings 93 of the section 86 for locking the sections 85 and 86 in any desired adjustment. The bolts 92 and 92' are yieldably projected by means of springs 94 but are positively retracted or projected by means of toggle links 95 pivoted to each other and to the bolts and also pivoted at their point of connection to each other to one end of a releasing plunger 96. Each plunger 96 has its other end appropriately connected to an intermediate portion of an operating lever 97 and one end of each lever 97 is fulcrumed as at 98 on one of the sections of the leg 10 while the other end of each lever 97 is connected to a control line 99 leading to the operator's cab. The levers 97 are reversely or oppositely positioned to avoid fouling of the control lines 99. When the boom is raised or lowered the spud or stiff leg 10 may be adjusted as to length by retracting bolts 92 or 92' or both and then raising and lowering the booms as may be desired, after which the

bolts are released and projected into registering openings of the sections 85, 86 and 87.

When the crane 7 is moved it is desirable to lift the adjustable leg 10 above the ground and to carry it along with the boom. This may be accomplished by disconnecting a haul-in line from its crawler wagon and attaching it as indicated at 100 to the lower section 87 of the spud or strut 10. Then by releasing one or more pairs of bolts 92 and 92' and reeling up the line 3 in an appropriate amount the strut or spud 10 may be shortened and its weight carried by the boom without subjecting its pivotal connection to the boom to unduly heavy stress. In operation after one crawler wagon has been loaded by the excavator 1 the operator on the loaded wagon signals the operator in the cab 80 and the operator on the hoist 12. The operator in the cab 80 then starts up the appropriate drum 8 on the crane and the loaded wagon is hauled from its position adjacent the borrow pit back to the point on the levee site at which the dirt is to be deposited. 80

During its travel, each crawler wagon is steered by the operator riding thereon, the steering being accomplished by applying one or the other of the brakes 25, thus causing the wagon to veer to one side or the other of the line of pull of the cable 3 or 4 depending upon the direction in which the wagon is moving. This feature of having each wagon independently steered enables a single crane and a single hoist to act through haul-in lines and haul-back lines to move a plurality of wagons and avoids interference of the wagons one with the other. 90

When the loaded crawler wagon reaches the point of deposit the operator thereon applies both brakes 25 and releases the brake 66 and pawl 73 so that further hauling in of the line 3 will slide the gate 20 along the wagon body and positively discharge the dirt out through the open end of the wagon. After this has been done the line 3 is permitted to pay out as the line 4 is hauled back so that the gate will be repositioned. Thereupon the brakes 25 are released and the brakes 63 and pawl 74 engaged or applied and the line 4 wrapped around its drum to haul back the wagon to the excavator. During this time the excavator has been engaged in leading the other crawler wagon so that continuous digging is effected and at the same time the earth as fast as it is excavated is transferred in a speedy and effective manner to the levee site. 105

The invention claimed is:

1. A system for building levees of the type including an excavator for taking earth from a borrow pit and comprising a plurality of mobile carriers, means for hauling the mobile carriers in from the borrow pit to the levee site and consisting of a haul-in line for each mobile carrier, an excavator crane having high 115

speed drums to which the haul-in lines are connected and having a boom over which the haul-in lines are guided, a leg supporting the upper and outer end of the boom from the ground and imparting stability to the crane, an operator's cab carried by the upper and outer boom and having control levers connected to the various instrumentalities of the crane, and means for hauling the mobile carriers back from the levee site to the borrow pit.

2. A system for building levees of the type including an excavator for taking earth from a borrow pit and comprising a plurality of mobile carriers, means for hauling the mobile carriers in from the borrow pit to the levee site and consisting of a haul-in line for each mobile carrier, an excavator crane having high speed drums to which the haul-in lines are connected and having a boom over which the haul-in lines are guided, a leg supporting the upper and outer end of the boom from the ground and imparting stability to the crane, an operator's cab carried by the upper and outer end of the boom and having control levers connected to the various instrumentalities of the crane, a haul-back hoist having a plurality of drums, and haul-back lines controlled by the drums and connected to the mobile carriers for hauling the mobile carriers back from the levee site to the borrow pit.

3. An excavating system of the character described including a crawler wagon having a body and free running endless flexible treads supporting said body, said body having one end open and having a gate slidably longitudinally thereof and operable to close one end of the wagon and to traverse the body thereof to discharge the contents of the wagon through the open end of the latter, haul-back and haul-in lines connected to said sliding gate, means for reeling up and paying out said haul-back and said haul-in lines, releasable means for holding the sliding gate against movement and means for braking the endless flexible treads whereby the haul-back and haul-in lines may be selectively operated to move the carrier bodily or to move the sliding gate relative to the carrier.

4. An excavating system of the character described including a carrier having free running traction elements and having a movable gate operable when moved relative to the body to discharge the contents thereof, haul-back and haul-in lines connected to the movable gate, means for reeling up and paying out said lines, releasable means for holding the gate against movement and braking mechanism for the traction elements whereby the lines may be selectively operated to move the carrier bodily or to dump the contents thereof.

5. An excavating system of the character described, comprising a mobile power excava-

tor, a plurality of mobile carriers, hauling lines connected to the carriers, a haul-back hoist connected to certain of said lines, a crane connected to the remainder of said lines, means coacting with the boom of the crane to impart stability thereto, and an operator's cab supported upon the boom of the crane and having controls connected to the conventional controls of the crane in any adjustment of the boom.

6. An excavating system of the character described, including a mobile carrier, a hauling line connected to the carrier, a power crane having the usual revolving platform and boom and having a high speed drum mounted on the revolving platform, said boom having a guide over which the hauling line is extended, said hauling line being secured to and wrapped around the said high speed drum, and means for imparting stability to the boom and crane and comprising a spud made up of a plurality of sections releasably secured together in any of a plurality of adjustments, the upper section being connected to the boom, and a base connected to the lower section.

7. In a system of the character described, means for hauling a mobile carrier comprising a power crane, a hauling line actuated by the crane and connected to the carrier, said hauling line being extended over the boom of the crane, and means for imparting stability to the boom and to the crane and consisting of a spud interposed between the boom and the ground and made up of a plurality of telescoped sections and releasable means for securing the sections in a plurality of adjustments.

8. In a system of the character described, means for hauling a mobile carrier comprising a power crane, a hauling line actuated by the crane and connected to the carrier, said hauling line being extended over the boom of the crane, and means for imparting stability to the boom and to the crane and consisting of a spud interposed between the boom and the ground and made up of a plurality of telescoped sections and releasable means for securing the sections in a plurality of adjustments, and including spring projected bolts, said sections having registered openings with which the bolts are adapted to coact, plunger operated toggles connected to said bolts, reversely positioned operating levers connected to said levers, and control lines connected to said levers.

9. An excavating system of the character described including a plurality of crawler wagons each having a body and a pair of free running flexible treads supporting said body, individually operable braking mechanisms for each flexible tread whereby each crawler wagon may be independently steered, haul-back and haul-in lines connected to said

70

wagons, and means for reeling up and paying out said haul-back and said haul-in lines.

10. An excavating system of the character described including a plurality of crawler wagons each having a body and a pair of free running flexible treads supporting said body, individually operable braking mechanisms for each flexible tread whereby each crawler wagon may be independently steered, haul-back and haul-in lines connected to said wagons, a power crane connected to said haul-in lines and a haul-back hoist connected to the haul-back lines.

11. An excavating system of the character described including a crawler wagon, having a body and free running endless flexible treads supporting said body, said body having one end open and having a gate slidably longitudinally thereof and operable to close 20 one end of the wagon and to traverse the body thereof to discharge the contents of the wagon through the open end of the latter, a haul-in line having branches connected to the forward side of the sliding gate, guide pulleys 25 on said wagon body around which the branches of the haul-in line are trained, a haul-back line, a shaft mounted at the rear of the body and having a drum about which the haul-back line is wound, other drums 30 controlled by said shaft and connected to the rearward side of the sliding gate, releasable holding means for said shaft, and braking means for the endless flexible treads, whereby the haul-back and haul-in lines may be 35 selectively operated to move the carrier bodily or to move the sliding gate relative to the carrier.

In witness whereof, I hereto affix my signature.

GWYNN L. LILLARD.
